UNITED STATES PATENT OFFICE.

EMIL ZAVITOVSKY AND CHRISTIAN J. LINS, OF MILWAUKEE, WISCONSIN, ASSIGNEES
TO MCKANE-LINS COMPANY, OF MILWAUKEE, WISCONSIN, A CORPORATION OF WIS-
CONSIN.

DESIGN FOR A CORNER PIECE FOR A TRUNK OR SIMILAR ARTICLE.

Application filed June 7, 1928. Serial No. 27,038. Term of patent 7 years.

To all whom it may concern:

Be it known that we, EMIL ZAVITOVSKY and CHRISTIAN J. LINS, citizens of the United States, residing at Milwaukee, in the county of Milwaukee and State of Wisconsin, have invented a new, original, and ornamental Design for a Corner Piece for a Trunk or Similar Article, of which the following is a description, reference being had to the accompanying drawing, forming part thereof.

In the drawing Fig. 1 is a perspective view of a corner piece for a trunk, or similar article, and Fig. 2 is a side view thereof.

We claim:

The ornamental design for a corner piece for a trunk or similar article, as shown.

EMIL ZAVITOVSKY.
CHRISTIAN J. LINS.
